UNITED STATES PATENT OFFICE.

ACHILLE F. BIAVATI, OF NEW YORK, N. Y.

OBSERVATION-CAR.

1,057,919.

Specification of Letters Patent.

Patented Apr. 1, 1913.

Application filed October 4, 1912. Serial No. 723,884.

To all whom it may concern:

Be it known that I, ACHILLE F. BIAVATI, a citizen of the United States, and a resident of the city of New York, borough of 5 Manhattan, in the county and State of New York, have invented a new and Improved Observation-Car, of which the following is a full, clear, and exact description.

This invention relates to improvements in 10 amusement devices, and particularly to what are known as observation wheels, and has for an object to provide an improved structure having a self-balancing car arranged with means for rotating the same in various 15 directions while the wheel structure is rotating.

Another object of the invention is to provide an observation wheel with a plurality of independently rotating cars arranged to 20 remain in a vertical position by gravity and by such action transmit power to propelling mechanism for propelling the car a certain number of turns in one direction in a horizontal plane, and then a certain number of 25 turns in an opposite direction.

In carrying out the objects of the invention, a wheel structure of any desired kind is provided having suitable bracing members. To this wheel is connected a plurality of rings, the rings being stationary 30 in respect to the wheel and acting as guides with tracks for cars mounted therein. These cars are formed with suitable seats to act as the usual observation car, and acting 35 through gravity will remain in a vertical position and allow the ring or track supporting the same to move as the main or large wheel moves. A plurality of gears are provided and also a plurality of racks so 40 arranged and associated together and with the respective cars and the wheel, as to cause the cars to rotate in a horizontal plane. These gears and racks may be so set as to cause the cars to rotate in a single direction 45 in the horizontal plane, or rotate a certain number of revolutions in one direction and then reverse themselves and rotate a certain number of revolutions in the opposite direction. Arranged in the car are one or 50 more seats which rotate with the car in its horizontal movement and also a seat which does not rotate in a horizontal plane so that when in use the patrons may use either seat.

A practical embodiment of the invention 55 is represented in the accompanying drawings forming a part of this specification, in

which similar characters of reference indicate corresponding parts in all the views.

Figure 1 is a side view of a wheel embodying the invention; Fig. 2 is a side view 60 of the car and the supporting ring therefor; Fig. 3 is a longitudinal vertical section through the structure shown in Fig. 2; Fig. 4 is a section through Fig. 3 on the line 4-4; Fig. 5 is a section through Fig. 3 on 65 the line 5-5; Fig. 6 is a plan view of the upper framework of the car shown in Fig. 3; and Fig. 7 is a fragmentary sectional view on the line 7-7 of Fig. 3, the same showing the bottom of the car, the tracks 70 and steps and associated parts.

Referring to the accompanying drawings by numerals, 1 indicates the wheel which may be of any size and of substantially any construction. The wheel 1 is supported 75 upon a suitable journal 2, which in turn is held properly in position by uprights 3. Arranged near the periphery of the wheel 1 is a plurality of rings or tracks 4 which are rigidly secured to the wheel 1 so as to be 80 stationary in respect thereto. The respective cars 5 are adapted to be positioned in the respective rings 4 and guided and held in place thereby. The cars are made heavier at the bottom than at the top or sides so 85 that the same will naturally remain normally in a vertical position under the action of gravity so that the bottom of the cars will remain substantially in a horizontal position. In order to cause the cars 5 to better 90 act under the law of gravity, a plurality of double flanged wheels 6 are mounted in suitable guides 7 which are secured in any suitable manner to the framework of the cars 5.

The framework 8 of the cars 5 has rigidly secured thereto an upper frame 9 and a lower frame or bottom 10. These upper and lower frames of course are rigidly secured to the frames 8 and move therewith. Arranged on the frame or bottom 10 is a circular track 11 and a pair of steps 12 and 13. The track 11 is designed to accommodate any desired number of flanged wheels 14 connected with the floor 15 of the horizontally moving part of the car in which seats 16 are placed. Arranged centrally of the floor 15 is a second floor 17 rigidly secured to a seat 18. The seat 18 is supported by a bar 19 clamped to the bottom of the flooring 10 by suitable nuts 20 and 21 whereby the floor 17 and associated parts are held

stationary in respect to the bottom or floor-
ing 10 and consequently will always remain
in a vertical position without independent
rotation. The floor 15 and seats 16 are con-
nected with a suitable housing 22 which is
provided with an upper portion or top 23
having rigidly secured thereto a shaft 24.
The shaft 24 is rigidly connected with the
beveled gear 25 meshing with the pinion 26
which is rigidly secured to the shaft 27.
The shaft 27 does not extend entirely across
the car but substantially to a central point
so that one of the gear wheels 29 will operate
shaft 27 and pinion 26, which in turn
will operate gear wheel 25 in one direction.
The pinion 26' is arranged opposite pinion
26 and is connected with a shaft 27' which
is mounted or supported by suitable brackets
28 which carry a pinion or gear wheel 29 in
a similar manner to the shaft 27, but is
adapted to cause the operation of the gear
wheel 25 in an opposite direction to the
way that gear wheel 26 moves the same.
The gear wheels 29 are adapted to engage
at various times the racks 30, 31, 32 and 33.
These racks are rigidly secured to the rings
4 so that as the big wheel 1 rotates the various
racks may engage the respective wheels
29 at different times for rotating the same.
It will be observed that the racks 32 and 33
are arranged on opposite sides, and racks
30 and 31 are arranged on opposite sides so
that only one of the wheels 29 may engage
a rack at any one time and that while en-
gaging alternately racks on opposite sides
of the car the cage or framework 22 will be
rotated in opposite directions in a horizontal
plane. It will be observed from Fig. 4 that
there is a space between the various racks so
that when one of the gear wheels 29 is dis-
engaged from rack 30 there will be an in-
terval before the opposite gear wheel 29 will
engage rack 33. This will give the cage or
housing 22 and seats 16 time to stop its ro-
tary movement or substantially stop the
same. From Figs. 3 and 4 it will be seen
that when power is transmitted from one of
the gear wheels 29 the same will be trans-
mitted through shaft 27, pinion 26, beveled
gear 25, and shaft 24 to the housing or cage
22. The rotation of the housing or cage 22
will not in any way affect the seat 18 and as-
sociated parts.

A suitable banister or railing 34 is pro-
vided so that during the movement of the
housing or cage 22 no one will accidentally
fall on to seat 18. Also it will be observed
that suitable gates 35 are provided for pre-
venting any one from accidentally falling
out of the car.

It will be evident that a greater or less
number of racks could be provided so as to
change or vary the number of horizontal
revolutions of the housing or cage 22 and
that other minor changes could be made

without departing from the spirit of the
invention.

Having thus described my invention I
claim as new and desire to secure by Let-
ters Patent:—

1. The combination of a wheel, a plurality
of car supports mounted on said wheel and
adapted to bodily turn with said wheel, a
car rotatably mounted within each of said
supports, and means for causing said car to
be of greater weight at the bottom than at
the top whereby the car will remain nor-
mally in a vertical position while said wheel
is rotated.

2. In an observation wheel of the class de-
scribed, the combination of a wheel struc-
ture, a plurality of rings arranged on said
wheel structure adapted to be carried thereby,
said rings being stationary in respect to
said wheel structure, a car mounted in each
pair of said rings, said car being heavier at
the bottom than at the top whereby the car
is adapted to remain in the same vertical
position under the action of gravity, anti-
friction means for each of said cars engag-
ing said rings whereby said rings act as
tracks for said car, a rotatable cage arranged
in each of said cars and means for transmit-
ting power from said wheel to each of said
cages for causing a horizontal rotary move-
ment of said cages.

3. In an observation wheel of the class de-
scribed, a wheel structure, a plurality of cir-
cular tracks rigidly secured to said wheel
structure, a car for each pair of said tracks,
means for holding said car on said tracks,
said cars being heavier at the bottom than
at the top whereby the cars are adapted to
remain upright continually under the action
of gravity, an independent rotatable cage
arranged in each of said cars, and a plu-
rality of means for transmitting power from
said wheel to said cage for rotating the same
independently of the rotation of said wheel.

4. In an observation wheel of the class de-
scribed, a wheel structure, a plurality of
guiding rings rigidly secured to said wheel
structure, a car rotatably mounted in each
pair of said rings having a weighted bottom,
the rotatable mounting of said cars and the
weighted bottom causing said cars continual-
ly to remain in a vertical position notwithstanding
the rotation of said wheel, an inde-
pendent rotatable cage arranged in each of
said cars, a gear wheel secured to said cage,
a rack secured to said rings, and means for
connecting said gear wheel and said rack
whereby when said wheel is rotated power
will be transmitted through said rack and
said gear wheel to said cage for rotating the
same with a movement independent of the
rotation of said wheel.

5. In an observation wheel of the class de-
scribed, a wheel structure, a plurality of
guiding rings rigidly secured to said wheel

- structure, a car mounted in each pair of said rings and guided thereby said cars being weighted at the bottom so as to remain continually in a vertical position notwithstanding the rotation of said wheel structure, a rotating cage arranged in said cars, a plurality of spaced racks secured to said rings on opposite sides of said cars, a shaft extending across said cars, a gear wheel secured to each end of said shaft and adapted to alternately engage said racks, a pinion connected with said shaft, and a gear wheel meshing with said pinion connected with said cage whereby power is transmitted from said wheel structure to said cage for rotating the same in a horizontal plane and in reverse directions for a predetermined number of revolutions.
6. In an observation wheel of the class described, a rotatable wheel structure, a plurality of pairs of rings rigidly secured to said wheel structure, said rings acting as tracks, a car for each of said pairs of rings, a plurality of antifriction guiding wheels connected with each of said cars engaging said rings, said cars being heavier at the bottom than at the top whereby the cars will remain continually in a vertical position, a rotating cage mounted on each of said cars, a track for supporting said cage, means for rotating said cage, a shaft for moving said means, a gear wheel connected to each end of said shaft, and a plurality of spaced racks secured to each of said rings, the racks of each pair of said rings being arranged alternately on opposite rings so that said gear
- wheels will engage successively said racks and consequently transmit power to said cage for rotating the same, a certain number of revolutions in one direction and then 40 rotating the cage in a certain number of revolutions in an opposite direction.
7. In an observation wheel of the character described, a rotating wheel structure, a plurality of car supports arranged thereon, a plurality of cars supported by said car supports, said cars being heavier at the bottom than at the top thereby remaining continually by gravity in a vertical position, a rotating cage arranged on each of said cars, a seat and platform arranged interiorly of each of said cages stationary in respect to said cars, and means for transmitting power from said wheel structure to said rotating cage for rotating the same.
8. The combination of a rotatable wheel, a plurality of car supports mounted on said wheel and adapted to bodily turn with said wheel, cars rotatably mounted on said supports having greater weight at the bottom 60 than at the top, whereby the bottom of the cars will remain substantially horizontal during the rotation of said wheel, and an independently rotatable cage positioned in each of said cars.

In testimony whereof I have signed my name to this specification in the presence of two subscribing witnesses.

ACHILLE F. BIAVATI.
